METHOD OF PULLING OVER BOOTS AND SHOES

Euclid I. La Chapelle, Brockton, Mass.

Application June 21, 1939, Serial No. 280,295

1 Claim. (Cl. 12—145)

My invention relates to the shoemaking art and more particularly to methods of pulling over boots and shoes.

The pulling over operation is well recognized to be the most important step of the lasting operation and whether it be performed by machine or by hand, the toe-end of the upper is, invariably, first to be engaged and strained, and thereby the entire upper, directly from the heel-end of the last is strained lengthwise of the last. The pulling over machine only can give the extreme degree of lengthwise strain necessary for properly moulding the box-toe and the upper to the toe-end of the last, and which is necessary also to bring about a firm setting of the counter and upper on the heel-end of the last. The high degree of strain upon the toe-end of the upper by the pulling over machine is such, and properly so for the reasons above stated, that, notably in the case of high toe lasts, the throat of the vamp stands away from its proper normal position down the instep of the last and the vamp of the upper, back of the toe of the last, between the throat of the vamp up to near the tip line of the upper (or between the ball and the corners of the toe of the last) stands also away from the top of the last after the toe-end pulling movement upon the upper has taken place and after the performance of the pulling over operation at the toe of the last. Under this defective condition the pulled over shoe, and the finished shoe, fail in embodying the exact shape of the last at that very prominent portion of the shoe. Then, in shoemakers' parlance, the upper is said to "drum" back of the toe and, aside from lacking in style at that point, the forepart of the shoe will not long remain in original shape during wear, thus increasing the lack of style at this prominent portion of the shoe.

Many attempts have been made from time to time towards eliminating the cause of this defective condition at pulling over machines (including attempts of that nature made by myself as shown in patents in my name) but, as the toe-end of the upper then could not be strained with the high degree of lengthwise strain required for proper moulding of the box-toe for proper final toe lasting and proper heel-seat formation, the conclusion then is, and must be, that the raising of the upper away from the last, as above explained, is a necessary evil that can be eradicated only after the pulling over machine operation at the toe.

I have, therefore, brought forth a novel method of pulling over which is solely directed to the

pulling over of boots and shoes that are pulled over by machine as the defective conditions herein noted do not exist when shoes are pulled over by hand since the toe-end pulling movement upon the upper then is incomparably less strenuous than by machine.

In the practice of my novel method I eventually engage and press against the top of the last, in the hollow, back of the toe, the upstanding portion of the vamp of the upper of a shoe already pulled over by machine at the toe and while that portion of the vamp of the upper is being held in pressed condition against and conformed to the top of the last, in then, preferably, performing the pulling over step at the ball line of the last by straining the marginal portion of the upper at the ball line of the last to set the throat of the vamp further down on the instep of the last and to distribute the fullness of the vamp at the shankpart towards the forepart of the last, by the well known "Ramsey pull" herein further explained, and in then fastening in pulled over condition on the last those portions of the upper and in then performing the pulling over step between the ball and the corners of the toe of the last, by straining the adjacent marginal pressed portion of the vamp of the upper at each side of the last and by then fastening in pulled over condition on the last those portions of the upper.

In thus pulling over the entire forepart, the shoe is better prepared for the side lasting machine operation than heretofore possible and, moreover, the side lasting operation upon welt shoes, such as of the well known Goodyear welt type, may be thereby eliminated, as herein further explained.

The difficulties encountered in properly pulling over the aforesaid back of the toe portions of the upper are such that the pulling over machine operation has always been performed, in the general runs of shoe factories, at the toe only, as herein shown in Fig. I, of the drawing, the toe-end grippers of the pulling over machine first engaging and very strongly straining (incomparably stronger than in pulling over by hand) the toe-end of the upper from the heel-end of the last, while the forepart of the upper is free of the last and is therefore moved away from the top of the last under the influence of the strong toe-end pulling movement upon the upper, thus making extremely difficult, after the performance of the pulling over machine operation at the toe, the setting of the throat of the upstanding vamp in proper position down on the

instep of the last and the setting of the upstanding vamp of the upper against the top of the last, in the hollow, back of the toe.

Moreover, although many attempts have been made from time to time to adapt pulling over machines to perform the pulling over operation of the entire forepart of the shoe, none, so far as I am aware, has ever been successful in a commercial sense.

One of the reasons for failure in this respect being that for a proper pulling over operation in the hollow, back of the toe of the last, the upper must first be pulled at the ball line of the last and then a compound pulling movement is required i. e. first upwardly edgewise of the last and then, by a turn of the grippers, diagonally toewards from the heel-end of the last (this compound pulling movement being known in the trade as the "Ramsey pull") and that no mechanical means adaptable to properly perform this compound pulling movement have yet successfully been devised in a pulling over machine. A further reason being that, in any event, under the high degree of strain required at the pulling over machine operation for properly setting the vamp of the upper against the top of the last, in the hollow, back of the toe, (especially in the case of a high toe last) the vamp-lining would be torn apart and thus the shoe would be irreparably damaged.

As a matter of fact, this compound pulling movement must be performed by hand, as the element of judgment also enters into it and comes pretty near being absolutely necessary preparatory to the pulling over of the vamp of the upper, between the throat of the vamp and the tip line of the upper, as, aside from bringing down the throat of the vamp in proper position on the instep of the last, the fullness of the vamp along the shankpart is thereby also advantageously distributed towards the forepart of the last.

In ordinary practice, immediately after the performance of the pulling over machine operation at the toe or, in any event, prior to the performance of the side lasting machine operation, the shoe is set and supported on a last-engaging spindle only and is then pulled over at the ball line only and by the compound pulling movement above explained and, invariably, by hand with ordinary lasting pincers and is fastened with tacks in pulled over condition on the last. In thus pulling over at the ball line of the last, the throat of the vamp, (or the ends of the quarters of a Blucher style upper) is advantageously set downwardly on the instep of the last but that portion of the upper, between the throat of the vamp and the tip line, is still left in its original defective state—away from the top of the last; and although reliance is placed upon the side lasting machine to force and set that upstanding portion of the vamp of the upper firmly against the top of the last, in the hollow, back of the toe of the last, in the ordinary performance of the side lasting machine operation (except in the case of lasts having very little slope from the toe crown to the instep or in the case of very stretchy uppers, such as of kid leather) this portion of the shoe will still remain in a more or less defective condition after the performance of the side lasting machine operation.

It is important to state that my novel method of pulling over is notably valuable in making possible the adoption by shoe manufacturers of a greater range of different style lasts regardless of the height of the toe of the last. Styles

in lasts now are limited as to height of toes or irregular shapes of instep, by shoe manufacturers who, due to the difficulty of bringing down the throat of the vamp over the instep of the last or of bringing down the vamp against the top of the last, in the hollow, back of the toe, are reluctant in adopting lasts incorporating high toes or irregular shaped insteps. Moreover, aside from the style feature, high toe lasts are conducive to added comfort in boots and shoes and with the practice of my novel method, such lasts or lasts having irregular insteps need no longer be repressed.

It is also important to state that the cost of upper patterns is high and that the embodiment of the style of the last in the shoe depends a great deal upon the provision of the proper upper pattern for the intended last. The cost of providing the exact upper pattern for each style of last in the general run of a shoe factory is, however, prohibitive so that a single upper pattern is generally provided for a plurality of different style lasts and under this condition it is obvious that some uppers must lack in proper fitting qualities, especially at the forepart and then, even when ordinary medium or low toe lasts are in use there is difficulty in pulling over the throat of the vamp and in the hollow, back of the toe. It is under this condition that my novel method is also valuable in making possible the exact embodiment of the style of the last, at least, at the most prominent portion of the shoe, on top of the last, back of the toe.

Aside from making possible the exact embodiment of the style of the last in the shoe at these prominent points, my novel method renders the pulling over of these particular portions of the upper far less laborious than heretofore possible and also greatly lessens the usual necessitated extreme strain upon the vamp-lining when in the performance of the additional pulling over operation back of the toe, the upper is being strained at the sides of the forepart of the last, between the ball line inclusive and the corners of the toe, so that possibility of damage to the vamp-lining at these portions of the shoe, of common occurrence in ordinary practice, is quite remote.

It is a notable fact that since in ordinary practice, shoes that have been pulled over by machines are subsequently pulled over at the ball line by hand, as hereinbefore explained, the extra work involved in the practice of my method is therefore minor over this ordinary practice and especially so when comparison is made with the beneficial results attained.

The apparatus herein shown forms the patentable subject matter of a patent for an improvement in Shoe jacks, issued in the name of the applicant February 20, 1940, No. 2,191,079 and the said apparatus forms no part of my present method which may be practiced by any suitable mechanical means other than herein shown.

As shown in the drawing:

Figure 1 shows a longitudinal sectional view of a welt shoe after having been pulled over by machine and fastened in pulled over condition at the toe only, as in ordinary practice;

Figure 2 shows the said pulled over shoe positioned on my vamp-pressing apparatus with the upstanding throat of the vamp properly set in position on the instep of the last and the vamp, back of the toe, pressed against and con-

formed to the top of the last, in the hollow, back of the toe;

Figure 3 shows the same longitudinal sectional view as that of the shoe shown in Fig. 2 but herein shown in perspective to better show the location of the lasting tacks holding the upper in pulled over condition on the entire forepart of the last;

Figure 4 is a bottom plan view of the entire forepart of the shoe shown in Figs. 2 and 3 showing the upper pulled over and fastened in pulled over condition at both sides of the last; and

Figure 5 is a sectional detail view taken on line 5—5, Fig. 2, showing the vamp engaging portion of the vamp pressing member of my vamp-pressing apparatus.

As further shown in the drawing:

As shown in Figure 1, an ordinary shoe upper 1 has been pulled over on the last 2, by machine in the ordinary manner at the toe only and fastened in pulled over condition by the usual lasting tacks 3, inserted through the marginal portion of the upper, through the welt shoe insole 4 and into the last 2. As shown in Fig. 1, that portion 7 of the vamp of the upper, located between the throat 5 of the vamp and the tip line 6 of the upper, has been raised away from the top of the last, back of the toe, with the throat of the vamp, under the influence of the high degree of strain exerted upon the toe-end of the upper from the heel-end of the last by the toe-end grippers of the pulling over machine.

To properly pull over the portion 7, of the upper and the throat 5, of the vamp, I have provided the vamp-pressing apparatus shown in Fig. 2, which includes the support 8, rotatably mounted in the column 9. The said support 8 has at its upper end a rearwardly extended arm 10, upon which the rocking frame 12 is pivoted at 11. The said rocking frame has a rearwardly extended arm 13, in which slideways 14, are provided. The said slideways hold the block 15, which supports the last-pin 16, and, as shown, the said block is free to slide in the slideways 14, relatively to the vamp pressing member, herein shown in the form of a rubber pad 21 (preferably of medium hard rubber) so as to readily accommodate lasts of various sizes. The said rocking frame 12 also has a forwardly extended arm 17, to which the upper end of a heavy spring 18 is secured while its lower end is secured to the holding pin 19, extending from the support 8.

In order to rapidly and easily move the said rocking frame 12, against the strong tension of the heavy spring 18, preparatory to setting the shoe on the apparatus or to removing it therefrom, I have provided a forearm engaging member 20, which is supported on the rearpart of the extended arm 13, of the rocking frame 12.

The rubber pad 21, is preferably covered by a thin covering 22, which is in tube form and into which the rubber pad is inserted and which may be of any suitable material, such as of thin upper leather. As shown, the rubber pad and the covering are set over a dove-tail shaped supporting member 23, which holds both in secured position. I have provided the ears 24, on the underface of the said supporting member 23, and I have provided a hole 25, to receive the pivot-pin 26, to which the upper end of the adjustable rod 27, is pivoted. This connection allows for oscillation of the vamp engaging pad 21, as best shown in Fig. 5, so as to readily adjust itself to various shapes of lasts. The rod 27, is adjustably se-

cured in the bracket 28, by the set-screw 29, the said bracket being secured to the support 8.

A bottom plan view of the entire forepart of the pulled over shoe is shown in Fig. 4, to better show the location of the fastenings at both sides 5 of the last and especially of the tacks 30, 31 and 32 holding the upper in pulled over condition on the last back of the toe, in accordance with my novel method of pulling over.

In the operation of the apparatus herein shown, the operator first rocks the frame 12, by pressing with his forearm upon the forearm engaging member 20, and he then sets the pulled over shoe, such as shown in Fig. 1, on the last-pin and the upstanding portion 7, of the vamp of the upper 15 upon the vamp-pressing member 21, by releasing the said member 20, and thus, under the influence of the heavy spring 18, the forepart of the shoe is forced towards the vamp-pressing member 21, and thus the upstanding throat 5, of the vamp of 20 the upper is properly set downwardly on the instep of the last and the upstanding portion 7, of the vamp of the upper is properly set against and conformed to the top of the last, in the hollow, back of the toe. Then, the operator proceeds to 25 pull over by hand with ordinary lasting pincers, first, preferably at the ball line of the last and, preferably, by the compound pulling movement hereinbefore explained, and he inserts fastenings to hold the upper in pulled over condition on the ball of the last and he next proceeds to pull over the sides of the upper adjacent to the pressed portion 7, of the vamp of the upper and he inserts fastenings to hold the pressed and conformed vamp of the upper and the adjacent sides 30 of the upper in pulled over condition on the last. Thus, the back of the toe portion of the shoe here-tofore most difficult to pull over properly, has been rapidly and easily pulled over and in the best possible manner and the forepart of the shoe 40 for the first time has been pulled over in its entirety, as shown in Figs. 2 and 4 of the drawing.

As shown, described and claimed herein, my novel method necessarily involves the use of a 45 pulling over machine adapted to pull over the upper only at the toe-end and at the sides of the toe, as in general practice, since, as hereinbefore stated, only a shoe pulled over by machine may be pulled over strongly enough at the toe-end to cause that portion of the upper located over the 50 hollow, back of the toe of the last, to be moved away from the top of the last and permanently remain upstanding from the top of the last unless pressed and conformed to the top of the last as in the practice of that part of my method 55 where that portion of the upper located over the hollow, back of the toe of the last, is pressed and conformed to the top of the last by mechanical means, such as herein proposed.

In the case of a welt shoe of the well known 60 Goodyear type, such as herein shown for convenience, the forepart of which having been pulled over in its entirety, as herein shown, permits of the passing of the shoe to the welt sewing machine without need of side lasting, as the 65 welt-guide of the ordinary welt sewing machine is well adapted to then last in the unlasted shankpart of the shoe. But, whenever a thick or extra rigid box-toe is embodied in that type of a shoe, 70 then the shankpart need be lasted in the ordinary manner, as otherwise the upper would be raised away from the last along the unlasted shankpart under the influence of the strain incident to the toe wiping operation.

Although my novel method is intended for the proper pulling over of the throat of the vamp of the upper and for the proper pulling over of that portion of the vamp of the upper back of the toe 5 between the throat of the vamp and the tip line of the upper, it is to be appreciated that my method is primarily directed to the proper pulling over of the throat of the vamp and then of that portion of the upper, between the throat of the 10 vamp and the tip line of the upper, if the entire forepart is to be pulled over.

The best practice of lasting (which includes the pulling over step) dictates that the upper be strained with as nearly the same degree of strain 15 as possible at all points at the sides of the last, so that once removed from the last, the shoe will stand up uniformly all over. In the case of shoes that have been thus strained uniformly, the laborious treeing operation then may be dispensed 20 with as the main objective in treeing resides in the bringing about of the uniform upstanding of the entire upper once the last has been removed from the shoe. With this main objective in view, the hot iron is usually availed of to shrink down 25 to the last any upstanding portion of the upper but in so doing, the upper is more or less damaged and, in any event, at portions of the shoe subjected to definite strain during wear, the results are not permanent. It is obvious that in ordinary 30 practice, the upper, including its lining, must necessarily be disadvantageously overstrained between the throat of the vamp and the tip line of the upper after the performance of the pulling over machine operation at the toe and 35 that my method of applying pressure upon that said back of the toe portion of the vamp, to a great extent eliminates the objectionable reoverstraining of the upper and of its lining at that part of the shoe, which is in line with the elimination 40 of the treeing operation at least at that aforesaid back of toe portion of the vamp of the upper.

All or nearly all lasts now in use by shoe manufacturers are of the hinged type (a last having a hinge connection uniting the forepart and the heelpart to allow the last to be "broken" and thus shortened at the last-pulling stage, so as to be easily removed from the shoe). There exists, however, a serious defective condition with the 45 use of such lasts, in that the hinge connection in due time wears loose on some of the lasts, so that a slight "break" of the last sometimes occurs at the pulling over machine operation under the influence of the toe-end pulling movement upon 50 the upper. Thus, such accidental "break" of the last being unknown to the operator of the pulling

over machine, the finished shoe on that particular last then is relatively shorter than the remainder of the shoes in that given case of shoes. My novel method, incidentally, eradicates this serious defective condition, as in applying pressure upon the vamp, back of the toe, after the pulling over machine operation at the toe, the slightly "broken" last is thereby straightened out into normal condition and there being no other possible accidental "break" of the last at any 10 subsequent shoemaking operation, this defective condition is permanently eliminated by the practice of my method.

Having thus explained the nature of my method invention and shown the best form of practicing the same now to me known, what I claim as new and desire to secure by Letters Patent of the United States is:

That method of pulling over, which consists in performing two distinct pulling over operations 20 upon a shoe, by providing an upper and a last; by passing the upper and the last to a pulling over machine adapted to pull over the upper at the toe-end of the last from the heel-end of the last and at the sides of the toe of the last, while the 25 upper is free of the forepart of the last, thereby moving away and leaving that portion of the upper located over the hollow, back of the toe of the last, away from the last and adapted to insert fastenings to hold the said pulled over toe portions of the upper in pulled over condition on the 30 toe of the last; by pulling over the upper at the toe-end of the last from the heel-end of the last and at the sides of the toe of the last, while the upper is free of the forepart of the last, thereby 35 moving away and leaving that portion of the upper located over the hollow, back of the toe of the last, away from the last and by inserting fastenings to hold the said pulled over toe portions of the upper in pulled over condition on the toe 40 of the last; by then performing an additional pulling over operation upon the upper by passing the pulled over shoe to an apparatus adapted to press and thereby conform to the last the said moved away portion of the upper; by pressing 45 and conforming to the last the said moved away portion of the upper; by pulling over the sides of the upper adjacent to the said pressed and conformed portion of the upper and by inserting fastenings to hold the said pressed and conformed 50 portion of the upper and the said back of toe adjacent side portions of the upper in pulled over condition on the last, preparatory to passing the pulled over shoe to a side lasting machine, substantially as shown and described.

EUCLID I. LA CHAPELLE.
